LOUIS H. MORIN, OF NEW YORK, N. Y., ASSIGNOR TO PHILLIPS-JONES CORPORATION, OF NEW YORK, N. Y., A CORPORATION OF NEW YORK.

FOLDING MACHINE.

Application filed September 2, 1925. Serial No. 54,035.

This invention relates to folding machines for fabrics and in particular to means for automatically controlling the duration of the folding operation.

In the operation of fabric folding machines now in common use, the length of time the article being folded is subjected to heat and pressure is determined by the length of time the operator holds his foot upon the operating pedal. The effect produced is thus dependent upon the judgment of the operator, a judgment not infrequently warped by an urge, doubtless innocent, toward high production when the recompense is on a piece basis, and by an urge toward low production when the recompense is fixed by the time of labor. In any event, in the folding of any given product, there is a certain period for the application of heat and pressure best suited to that product, any departure from which is disadvantageous. It is accordingly an object of the present invention to provide means set in motion by the operator for folding the fabric and holding it under heat and pressure, the release of the fabric being automatically effected after a predetermined length of time, and not under the control of the operator.

Machines of this type are commonly provided with a die having the shape of the article to be folded and a movable head of the same shape which is swung up out of the way, to enable the operator to place the fabric above the die, and is then swung down to force the fabric into the die and fold its overhanging edges upward. A plurality of slides are then moved inward to fold the edges of the fabric over the head. In accordance with the present invention the head when once set in motion is no longer under the control of the operator, and hence in the absence of some further provision for safety there would be the danger that the operator's hand might be caught and seriously injured. It is therefore a further object of my invention to provide safety means making it possible to arrest the movement of the head without affecting the operation of the rest of the machine.

In the accompanying drawings I have illustrated a preferred embodiment of my invention. In these drawings Figure 1 is a side elevation of a folding machine equipped with the timing control and the safety connection of the present invention; Figure 2

is a detail showing the relative position of the head, the slides and the fabric during the folding operation; Figure 3 is a plan view partly in section of the timing apparatus; Figure 4 is a detail of the safety connection; Figure 5 is a vertical section on an enlarged scale taken along line 5—5 of Figure 1; Figure 6 is an enlarged section taken along line 6—6 of Figure 1, and Figure 7 is a diagrammatic view of the head and operating connections showing the result of arresting the movement of the head.

The folding machine illustrated in Figure 1 comprises a bed 1 supported upon standards 2. The bed carries a die block 3 provided with a die cavity 4 having the shape of the article to be folded. Pivotaly mounted at the rear of the bed 1 is an arm 5 carrying at its forward and upper end a head 6 likewise having the shape of the article to be folded and designed, when swung downward, to fit within the die cavity 4 during the folding operation. Slidably mounted upon the die block 3, adjacent the die cavity, are a plurality of slides 7 designed to move over the cavity and the head during the folding operation. The article 8 to be folded is first cut to substantially the desired shape, but large enough to provide edges which are to be folded and placed above the die cavity, the head 6 moved down forcing the body of the article into the cavity, causing its edges 9 to assume a substantially vertical position as illustrated by dotted lines in Figure 2, and the slides 7 then moved inward folding the edges down upon the head, the parts then occupying the position illustrated in Figure 2.

The swinging movement of the arm 5 and the head 6 is effected by means of a link 11 provided at its upper end with a slot 12 which receives a pin 13 on the arm 5. The lower end of this link 11 is pivotally connected to a horizontal link 14 journaled upon a rod 15 mounted on the standards 2, and the head 6 normally held in raised position by means of a spring 16 connecting the link 14 with the frame of the machine. A final downward pressure of the head 6 against the fabric is effected by means of a cam operating in contact with the lower end 17 of the arm 5 and the mechanism is so timed that the slides 7 are moved inward at the same time or slightly after this pressure is applied. The exertion of this final pressure and the movement

of the slides is effected by fluid operated mechanism mounted below the bed and controlled by means of a valve 18 operated by a link 19 pivotally connected with the link 14. In machines now in common use the link 14 is extended beyond the machine and terminates in a pedal by means of which the operator controls the operation of the machine. Thus, when this pedal is depressed the link 11 is moved upward, swinging the arm 5 and the head 6 into contact with the fabric and through operation of the valve 18, controlled by link 19, the final pressure of the head is applied and the slides 7 are moved inward. The parts contacting with the fabric being heated, preferably, electrically, the fabric is thus held under heat and pressure in folded position. After being thus held for a period of time which, in the judgment of the operator, is sufficient to fix the fold, the operator releases his pressure upon the pedal, whereupon the spring 16 swings the link 14 downward thus operating the valve 18 and causing a withdrawal of the slides 7. At the same time the link 11 is moved downward until the upper end of the slot 12 contacts with the pin 13 and the arm 5 and head 6 are swung up and away from the die. The motion lost while the pin 13 is moving in slot 12 permits the withdrawal of the slides before the upward swinging movement of the head is initiated. The folded article is then removed from the head which is made collapsible for this purpose.

The foregoing is a brief description of a folding machine now on the market and of itself forms no part of the present invention. The operation of this machine is controlled wholly by the operator and the fabric is held under heat and pressure only so long as the operator keeps his foot upon the pedal. I shall now describe how, in accordance with the present invention, I automatically control the duration of the pressing and folding operation and thus make it independent of the judgment of the operator.

Mounted at the rear of the machine upon a shaft 21 is a cam 22 having a circular face for more than three-quarters of its circumference, but provided with a cut-out 23. Mounted within vertical guideways 24, just back of the cam, is a cam slide 25 provided with a slot 26 through which the shaft 21 passes. Mounted upon this cam slide is a roller 27 which acts as a cam follower so that the slide 25 is vertically reciprocated by the rotation of the cam. The link 11 is connected to this slide 25 by means which shall be described later. At present suffice it to say that the link 11 is reciprocated with the slide so that as the cam rotates the head 6 is swung into and out of operative position with relation to the fabric on the machine. The cam and the various connections are so designed that when the roller 27 lies within the bottom

of the cut-out 23 the head 6 is in raised position and when the roller is riding upon the circular face of the cam the head 6 is in lowered position. Thus, starting from the position illustrated in Figure 5, a single rotation of the cam will cause the head 6 to be swung downward into operative position where it will remain until the roller again rides down into the cut-out which movement will cause the head 6 to be swung upward again. It now remains to describe the single revolution-clutch mechanism which I employ for rotating this cam through a single revolution and then automatically stopping it.

The shaft 21 on which the cam 22 is mounted is driven by means of a motor 28 which, through suitable reduction gearing 29, drives a bevel pinion 31 meshing with a second bevel pinion 32 fixed upon a bushing 33 journaled on the shaft 21. The bevel pinion 32 is likewise fixed to a clutch sleeve 34 of a single revolution clutch, of known design, the idle member 35 of which is keyed to the shaft 21. The motor 28 is in constant rotation and so likewise is the clutch sleeve 34. Encircling the clutch sleeve 34 is a clutch band 36 provided with outstanding lugs 37 which contact with fingers 38 on the idle member of the clutch. When this clutch band 36 is tightened about the sleeve 34, the shaft 21 is therefore rotated and cam 22 with it. The clutch band 36 is provided with lugs 39 one on either end connected by means of a bar 41 provided at one end with a shoulder 42 which bears against a cut-out in a rotatable pin 43. This pin is rotated through a small arc by means of an arm 44 terminating in a roller 45. Encircling the idle member of the clutch is a fixed sleeve 46 supported upon an upright 48 and provided with a flange or integral annular collar 47. Loosely mounted upon this sleeve 46 is a collar 49 adjacent the flange 47 and of the same diameter. The collars 47 and 49 are each provided with cut-outs 51 in their peripheries which normally are in alignment and in both of which the roller 45 of the arm 44 normally lies. The collar 49 is provided with a depending arm 52 having a slot 53 which receives a pin 54 on an arm 55 fixed upon an oscillatable shaft 56, having a pedal 57 fixed to its outer end. Oscillation of this shaft 56 causes a partial rotation of the collar 49 which results in swinging the roller 45 and the arm 44 outward and a tightening of the clutch band 36 about the sleeve 34. The consequent rotation of this sleeve is transmitted to the shaft 21 and the cam 22 is rotated. As soon as this rotation begins, a spring 58 fastened at one end to the frame of the machine and at the other end to the shaft 56, returns the arm 55 to upright position and thus returns the collar 49 to its original position with relation to the collar 47. When the roller 45, after making one

revolution returns to its starting point, the two cut-outs 51 are in position to receive it and the clutch is thus released.

- Thus the operator by depressing the pedal 57 and oscillating the shaft 56 sets the cam 22 in rotation, and this cam, through roller 27, link 11 and link 14 and their associated elements moves the folding parts of the machine into and out of operative position.
- Once this movement is initiated, the operator is powerless to interfere and the fabric is held under heat and pressure for a period of time, the duration of which depends upon the speed of rotation of the shaft 21 and the configuration of the cam 22.

I shall now describe the safety connection by means of which the downward swinging movement of the head 6 may be interrupted without interfering with the operation of the machine. Pivotedly mounted upon a pin 65 in the upper end of the slide 25 is a yoked lever 59 carrying at one end a weight 61 and at the other end pivotally connected at 62 with a pair of members 63 which are in turn pivotally connected with links 11 and 14 by means of a common pivot pin 64. These members 63 terminate in curved portions provided with vertical slots 63' which receive the outer ends of the pivot pin 65. The weight 61 is of such magnitude and so mounted upon the lever 59 that it is normally counterbalanced by the spring 16. Thus, as the slide 25 rises and falls in response to the rotation of the cam 22 the lever 59 with its weight 61 and the member 63 likewise rise and fall and transmit this movement to the links 11 and 14. Should the operator inadvertently place his hand beneath the downwardly swinging head 6 this downward swinging movement is arrested. The lever 59 thereupon pivots about the point 62, but its upward movement is not interfered with, the slide 25 moving the pin 65 up slots 63', as shown most clearly in Figure 7. The cam 22 completes its cycle, the machine comes to rest in the usual manner, and no damage has been done either to the operator's hand or to the machine.

I claim:

1. In a folding machine the combination of fluid-operated means for applying pressure to a folded fabric, means under the control of the operator for initiating the action of said fluid operated pressing means, and means for automatically releasing the pressure after a predetermined time interval.

2. In a folding machine the combination of fluid-operated means for folding and pressing a fabric, a cam controlling the movement of said folding and pressing means, means under the control of the operator for starting the rotation of the cam to move the folding and pressing means into contact with the fabric and means for automatically stopping said cam after it has made one revolution and has moved the folding and pressing means out of contact with the fabric.

3. In a folding machine of the type in which a fabric is subjected to heat and pressure as long as the operator holds the pressing and heating elements in operative position, the combination of means set in motion by the operator for moving these elements into operative position, holding them in such position a predetermined length of time and then automatically removing them.

4. In a folding machine the combination of a movable head for folding and pressing a fabric, means set in motion by the operator for moving the head into operative position, holding it there a predetermined time and then automatically releasing it, and a yieldable connection between the head and the moving means so that the head may be stopped without interfering with the cycle of operations.

5. In a folding machine, the combination of means for applying pressure to a fabric, means for moving the pressure applying means into contact with the article being folded, and a counterbalanced pivoted lever intermediate the moving means and the pressure applying means which swings when movement of the pressure applying means is arrested without interfering with the operation of the moving means.

6. In a folding machine, the combination of a movable head for applying pressure to a fabric, a link for moving the head, a cam, a cam follower, a slide movable with the cam follower, and a counterbalanced lever pivotally mounted on the slide and pivotally connected with the link which moves the head, the arrangement of the parts being such that rotation of the cam reciprocates the head, but if the movement of the head is arrested the lever is pivoted about its connection with the link, without interfering with the rotation of the cam.

In testimony whereof I affix my signature.

LOUIS H. MORIN.
